DISPENSING CONTAINER FOR LAPPED SHEETS OF PAPER OR THE LIKE

Nathan Shapira, 555/308 Westwood Plaza,
Los Angeles, Calif. 90024

Filed May 15, 1967, Ser. No. 7,129

Claims priority, application Italy Feb. 3, 1967

Term of patent 14 years

(Cl. D52—2)

Fig. 1

Fig. 2

Fig. 3

Fig. 4

Fig. 5

Fig. 6

FIGURE 1 is a perspective view of a dispensing container for lapped sheets of paper in closed position, showing my new design;

I claim:

The ornamental design for a dispensing container for lapped sheets of paper or the like, substantially as shown.
